(57) **CLAIM**

An ornamental design for an illumination device, as shown and described.

DESCRIPTION

FIG. 1 is a perspective view of the illumination device illustrating top, side and end surfaces;

FIG. 2 is an elevation top view of the illumination device, with the wire broken away to indicate indeterminate length;
FIG. 3 is a view illustrating a lateral side surface of the illumination device;

FIG. 4 is a bottom view of the illumination device;

FIG. 5 is a view illustrating a lateral side surface of the illumination device;

FIG. 6 is a view illustrating one end surface of the illumination device; and,

FIG. 7 is a view illustrating the end surface opposing the end surface of FIG. 6.
